MARIE W. HUBER, OF SEATTLE, WASHINGTON

COMBINATION LAUNDRY TRAY AND WASHBOARD

Application filed June 5, 1930. Serial No. 459,307.

My invention relates to the art of laundry tray making and more particularly to a combination laundry tray and washboard.

Practically every modern home or apartment house has in its laundry, built-in tubs, normally termed laundry trays, which most usually consist of two similar basins formed in a single unit. These are usually made of cast material, bound together with cement.

10 Such trays are used, even although a washing machine is also provided, as it provides a convenient means for giving special attention to certain garments which may be unusually delicate or which may have been

15 soiled to an unusual degree, and to assist in this operation a conventional type of washboard is normally used. These are made of many materials and are very well known but all the various types rely upon a corrugated or ribbed surface to give a rough backing upon which to lay the garment as it is treated with soap and rubbed thereupon.

The use of a washboard in a laundry tray, while very common, is rather inconvenient, 25 and further as it must be held securely during the process of rubbing the clothes it usually tends to wet the operator about the waist line. When a washboard is used in a laundry tray it in effect reduces the effective size of 30 the same and further the feet of the washboard often injure a delicate fabric as it moves about somewhat during the rubbing operation. It is to overcome this general condition that I provided my combination 35 laundry tray and washboard, therefore:

The principal object of my invention is to provide a laundry tray which has the roughened surface normally found on a washboard and which is formed as an integral part of 40 the tray.

A further object is to provide the equivalent of a washboard which does not necessitate the operator holding the same in place when rubbing clothes.

45 A further object is to provide a soap ledge which is self-draining.

Other and more specific objects will be apparent from the following description taken in connection with the accompanying drawings, wherein:

Figure 1 is a top plan view of a double laundry tray, showing my improvement as embodied in each tray.

Figure 2 is a vertical cross-sectional view taken along the line 2—2 Figure 1.

Figure 3 is a longitudinal sectional view taken on a vertical plane substantially along the line 3—3 of Figure 2.

Figure 4 is an enlarged fragmentary section of a portion of Figure 3.

Figure 5 is an enlarged fragmentary view of a portion of Figure 2.

Referring to the drawings throughout which like reference characters indicate like parts, numeral 8 designates the main molded portion of a conventional laundry tray, which consists of the two basins 10 and 12. This tray may be supported in any convenient manner as by the metal stand 14 and has the usual water supply faucets 16, an overflow and the drain 18, which will normally at some point in its line have the conventional inverted U trap. This much of the laundry tray is a conventional design and forms no part of my present invention.

My invention resides in providing a ribbed, corrugated or otherwise roughened surface 20 and forming the same as part of the laundry tray when the same is manufactured. The exact nature of the roughened surface is a matter of individual preference and might be any of the various types found in washboards of the conventional type. The most preferred roughened surface would be one moulded into the laundry tray as it is cast. When moulded into a concrete tray the corrugations must not be too fine and further it is usually desirable to use a rather rich mixture at this point. Small pea gravel may be used to produce a very satisfactory surface.

Another form I have found very satisfactory is to make a corrugated metal sheet as will be more clearly understood by referring to Figure 5. This metal sheet 22 should be of some non-corrosive and rust proof material, such as brass, copper, zinc or the like, which is formed in regular corrugations and then imbedded in the laundry tray as it is manufactured. With certain materials such as baked or vitrified clay products, it is possible to

create a very fine roughened surface in the tray itself. This is also true of that type of construction which employs a metal base and which is covered with enamel. I have found, 5 however, that the cement-bound concrete construction is the most economical and very satisfactory.

Many manufacturers have very expensive molding equipment for producing laundry 10 trays, and in order to make it possible to use the principal parts of this equipment, I propose that when my corrugated plate is used that the front wall 24 have its outer surface 26 as is normally used, and that the thickness of 15 wall 24 be increased substantially as is shown in Figure 2. This gives the tray additional strength where the strength is desired, and also provides a more gradual slope for the surface 20, which is very desirable.

20 I have further found that persons accustomed to use a washboard, desire a place for the soap at the top of the board. To provide for this condition I formed in the upper portion of wall 24 a soap-receiving ledge or niche 25 28. The exact construction will be better understood from Figures 4 and 5, wherein the soap niche 28 is provided with a lower surface 30. This I have found should be substantially at right angles to surface 26. In 30 some forms I have used an upwardly extending lip at the outer edge forming the same as part of plate 22. This is not very satisfactory in that a new bar of soap is usually too wide to lie inside of it so I prefer the form 35 shown in Figure 5. I have in addition provided a water drain channel 32 which slants downwardly each way from the center of surface 20, as will be observed by the showing in dotted lines in Figures 3 and 4. This is 40 provided at each end with the discharge openings 34. While other methods of disposing of this waste water might be provided it is quite desirable that some definite means be employed for this purpose, otherwise the soap will soon dissolve and be reduced to a jelly-like substance, which is very 45 wasteful of the soap.

The foregoing description and the accompanying drawings clearly disclose a preferred embodiment of my invention but it 50 will be understood that this disclosure is merely illustrative and that such changes in the invention may be made as are fairly within the scope and spirit of the following 55 claim:

What I claim is:

The combination in a laundry tray having an inclined front wall and an inner inclined face on said wall, of a corrugated area on 60 said inner face forming a washboard, said wall having a niche in its upper portion above the washboard and extending the length of the washboard, the bottom wall of the niche being perpendicular to the plane of the washboard, said bottom wall declining laterally 65

from its center toward its ends and terminating in discharge openings from the niche.

In witness whereof, I have hereunto subscribed my name this 23rd day of May, A. D. 1930.

MARIE W. HUBER.
